UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed December 27, 1921. Serial No. 524,880.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates to the class of attachments to typewriters and similar type-impact machines in which plural record sheets are entered, held, and guided in spaced relation about the platen, and pass on each side of a manifolding member, whereby an original and a carbon copy may be produced.

The object of my invention is to provide simple and practical means for entering, holding and guiding in spaced relation and in association with the platen, plural record sheets, and for disposing between them at one portion of their forward feed, a manifolding sheet, adapted for presentation together with said record sheets in the line of type impact, whereby plural records may be made.

To this end my invention consists in the novel manifolding attachment which I shall hereinafter fully describe by reference to the accompanying drawings, in which—

Fig. 1 is an end view and part section of my attachment taken on the line 1—1 of Fig. 3.

Fig. 2 is a cross section on the line 2—2 of Fig. 3.

Fig. 3 is a front-elevation, broken, and partly in section of my attachment.

Fig. 4 is a front view of the innermost guide apron, the platen being omitted.

Fig. 5 is a sectional detail enlarged, showing the container and the fan-folded manifolding sheet therein.

Fig. 6 is a similar sectional detail, showing the manifolding sheet in the form of a roll, instead of fan-folded.

1 indicates a part of the platen-carriage of a typewriter, and 2 is the platen having a shaft 3 and thumb wheel 3', by which it is turned for line spacing and feeding the record sheets as usual.

4 is an outer guide-apron carried by the platen carriage and extending from a line back of the platen, downwardly to and under said platen. The apron 4 is aper-

tured along its rear portion as shown at 4', in Fig. 2, and through these apertures play the presser-rollers 5 which are carried by a shaft 6 mounted on the platen-carriage. 7 is a second apron which serves both as a record sheet guide and separator and as a carrier for the manifolding sheet. This apron is pivotally supported on a rod 7" of the platen carriage and extends thence under the platen. It lies between the platen and the first apron 4 and is spaced from both. It is apertured as shown at 7', in Fig. 2, its apertures registering with those of the apron 4, so that the presser-rollers 5 play through both sets of apertures. There may be one or more such aprons as 7. I have here shown two. The upper back portions of the apron 4 and the aprons 7 relatively diverge or flare as shown in Figs. 1 and 2 to afford convenience and accuracy in entering the record sheets as will be presently described. The aprons 7 terminate below the line of type impact, which line is indicated by the type 8, the index pointer 9, and the main inking ribbon 10 of the machine, as shown in Fig. 2.

The lower or free extremity of each apron 7 carries the manifolding sheet 11. This sheet may be of any suitable nature, preferably what is known as carbon paper, but instead of being in the form of relatively short separate sheets it is best a long strip or web having a width about equal to that of the record sheets. It may be carried by the aprons 7 in various ways, for example, as shown in Figs. 2 and 5, wherein it lies fan-folded in a container 12, formed in or on the lower end of the apron 7, said container having an exit opening 12' and a hinged cover 12", Fig. 5; or it may be carried as a roll 13 in the container or the apron 7 as shown in Fig. 6.

Upon the upper front of the platen-carriage, above the line of type-impact, I have shown impinging feed rolls 14 adapted to be operated by suitable means, as by the thumb-wheels 14', Fig. 3, to feed the carbon sheets forward.

15, in Fig. 2, indicates, in dotted lines, the record sheets of paper, there being three here shown, one for the original and two for the duplicates. These three record sheets are inserted in the flaring entrances between the apron 4 and the two aprons 7.

The outermost or original record sheet enters between the apron 4 and the outer one of the two aprons 7. The first duplicate record sheet enters between the two aprons

- 5 7, while the second duplicate record sheet enters between the inner apron 7 and the platen. When the platen is turned on its axis, the presser rollers 5, protruding through the apertures of the aprons 4 and 10 7 press all three record sheets against the platen, so that the rotation of the latter feeds the sheets forward, past the extremities of the aprons 7, and up around the face of the platen behind the index pointer and 15 main inking ribbon to and beyond the line of type-impact.

The two carbon sheets 11 having been drawn out in part from their containers and passed up between their feed rolls 14, lie between the original record sheet and between the two duplicate record sheets, respectively, as seen in Fig. 2, and as all sheets, both record and carbon, are thus presented in proper relative position in the line of type impact, an original and two copies of the record will be made.

In line spacing only the record sheets will be fed forward, the carbon sheets remaining stationary, but as occasion requires, said 30 carbon sheets may be drawn forward sufficiently to present fresh surfaces in the line of type impact, by manipulating the feed rolls 14.

In order to conveniently replenish the 35 store of carbon-paper, I mount the platen 2 upon arms 16 having a pivotal center at 17 on the platen carriage. The platen can thus be swung up, as shown by the dotted lines in Fig. 2, in order to expose the innermost carbon container; and the apron 7 which carries this container may also be swung up about its rod at 7", to expose the next container.

I claim:—

- 45 1. A manifolding attachment for typewriters, comprising an apron carried by the platen-carriage of the machine, and associated with the platen thereof to receive a record sheet and guide it in its forward feed; 50 a second apron carried by the platen-carriage in spaced relation to the first apron, to receive and guide a second record sheet and separate it from the first record sheet; and a manifolding sheet connected with the 55 second apron and adapted to lie between the two record sheets.

2. A manifolding attachment for typewriters, comprising an apron carried by the platen-carriage of the machine, and associated 60 with the platen thereof to receive a record sheet and guide it in its forward feed; a second apron carried by the platen-carriage in spaced relation to the first apron, to receive and guide a second record sheet and 65 separate it from the first record sheet; and a

manifolding sheet stored upon the second apron and adapted to be drawn therefrom as required to lie between the two record sheets.

3. A manifolding attachment for typewriters, comprising an apron carried by the platen-carriage of the machine, and associated with the platen thereof to receive a record sheet and guide it in its forward feed; a second apron carried by the platen-carriage in spaced relation to the first apron, to receive and guide a second record sheet and separate it from the first record sheet; a container carried by said second apron; and a manifolding sheet fan-folded in said container and adapted to be drawn therefrom as required, to lie between the two record sheets.

4. A manifolding attachment for typewriters comprising an apron carried by the platen-carriage of the machine, and associated with the platen thereof to receive a record sheet and guide it in its forward feed; a second apron carried by the platen-carriage in spaced relation to the first apron, to receive and guide a second record sheet and separate it from the first record sheet; a manifolding sheet stored upon the second apron and adapted to be drawn therefrom as required to lie between the two record sheets; and means for moving said manifolding sheet to present successive portions in the line of type impact.

5. A manifolding attachment for typewriters comprising a platen; means for mounting said platen on its carriage to adapt it to be swung into and out of functional position; an apron carried by the platen-carriage and partially encircling in spaced relation the lower arc of the platen when in functional position, said apron being adapted to receive a record sheet and guide it in its forward feed; a second apron on the platen carriage partially encircling the platen between it and the first platen and in spaced relation to both, said second apron being adapted to receive a second record sheet and separate it from the first record sheet; a manifolding sheet lying between the two record sheets beyond the extremity of the second apron; and means for mounting said manifolding sheet on the second apron adapting it to be drawn therefrom for use, said mounting means lying below the platen and adapted to be exposed when the platen is moved out of position.

6. A manifolding attachment for typewriters comprising a platen; an apertured apron to receive a record sheet and guide it in its forward feed; a second apertured apron between the first apron and the platen and in spaced relation to both, said second apron being adapted to receive a second record sheet and separate it from the first record sheet; presser - rollers operating

through the apertured aprons to hold the two record sheets in contact with the platen to effect the forward feed of the two sheets; and a manifolding sheet carried by the second apron and adapted to lie between the two record sheets.

7. A manifolding attachment for typewriters comprising an apron carried by the platen-carriage of the machine and associated with the platen thereof to receive a record sheet and guide it in its forward feed; a second apron carried by the platen-carriage in spaced relation to the first apron, to receive and guide a second record sheet 15 and separate it from the first record sheet;

a container carried by said second apron; and a manifolding sheet housed within said container and adapted to be drawn therefrom to lie between the two record sheets.

8. In a manifold attachment for typewriters, a chambered apron carried by the platen carriage of the machine and associated with platen thereof to receive and guide a record sheet in its forward feed; and a manifolding member housed within the 25 chamber of said apron.

In testimony whereof I have signed my name to this specification.

MALCOLM L. COSSITT.
